UNITED STATES PATENT OFFICE.

HENRY L. GUENTHER, OF LOS ANGELES, CALIFORNIA.

VARIABLE-SPEED CAN-FEED MECHANISM.

Application filed December 21, 1921. Serial No. 523,825.

To all whom it may concern:

Be it known that I, HENRY L. GUENTHER, a citizen of the United States, residing at Los Angeles, in the county of Los Angeles and State of California, have invented new and useful Improvements in Variable-Speed Can-Feed Mechanism, of which the following is a specification.

This invention relates to a can feed mechanism for can seaming machines and particularly pertains to a variable speed feed mechanism.

At the present time filled cans and their caps are fed to a seaming machine where the cans and caps are double seamed together. The speed of the machine is such as to often cause the contents of the can to spill and for this reason the machine must necessarily run comparatively slow.

It is the principal object of the present invention to provide a high speed seaming machine and to deliver cans and their caps thereto in such a manner as to prevent the spilling of the contents of the cans and at the same time to insure that the cans and caps will be co-incidently delivered to the machine at a high speed and without probability of spilling.

The present invention contemplates the use of initial can feeding mechanism which will convey a flow of can bodies to the main can and cap feed device where the cans will be engaged and will be carried forward at a gradually increasing rate of speed until they have come into register with a can cap after which they will be delivered at a continuous and even rate of speed to the can seaming machine.

The invention is illustrated by way of example in the accompanying drawing in which:

Figure 1 is a view in plan showing the complete feeding mechanism.

Fig. 2 is an enlarged view in perspective showing one of the can top feed members.

Fig. 3 is an enlarged view in vertical section showing the complete feeding mechanism and the drive therefor.

Referring more particularly to the drawings, 10 indicates the main frame of a seaming machine. This frame is provided with a plurality of vertically aligned bearings for receiving the various shafts of a cap and can-seam device. An upper bearing frame 11 is secured to the main frame 10 and further provides bearings. These include a feed disc

shaft 12 which carries the circular feed disc 13. This disc receives a flow of cans and by frictional engagement therewith delivers them into the machine. A central hub 14 is formed above the face of this disc, this hub being provided with a plurality of yieldable fingers 15 which may consecutively engage the cans and positively feed them as assisted by the friction of the discs upon which they are supported. A side track 16 partially circumscribes the outer face of the disc while another track 17 extends across the disc to a point near the hub and completes a guide-way for can bodies which are to be delivered to the machine. The trackways 16 and 17 provide a sinuous path of travel for the can bodies and delivers them to a feed spider 18. This spider, as has been described in a co-pending application filed concurrently herewith and entitled "Can cap feed", is formed with a plurality of circumferential recesses 19 into which a can may partially seat. These recesses receive the can bodies and co-operate with a guide rail 20 to carry the can around the spider 18 and into the main turret spider 21 of the double seaming machine. The guide rail 20 is concentric with the spider 18 and is supplemented by an inner concentric guide rail 22 spaced therefrom. These two guide rails are of sufficient distance apart to accommodate a can cap and to support it as it is being fed forwardly to the double seaming machine.

Referring more particularly to Fig. 3, it will be noted that the guide rails are inclined toward the machine. This will insure that the can cap will gradually be forced on to the can, thus packing the contents of the can and delivering the two in close relation to each other when they are received by the main turret 21 of the double seaming machine.

It is the principal object of this invention to pick the cans up while moving at a very slow rate of speed on the feed disc 13 and to gradually increase the rate of travel of the can until they are delivered to the first turret of the double seaming machine.

This is brought about by a variable speed mechanism interposed between the disc 13 and the feed spider 19. This mechanism comprises a sprocket chain 24 which is led around sprockets 25 and 26. One run of the chain is caused to deviate from a direct path, tangent to the circumferences of the

two sprockets. This is brought about by a guide cam 27. Thus the lineal speed of travel of fingers 28 of the sprocket chain 24 will gradually increase from the pitch-line speed of the sprocket 25 to the speed of the feed spider 18. The sprocket chain carries a plurality of feed fingers 28. These fingers are provided to positively engage the cans delivered by the feed disc 13 and to carry them forward into register with the recesses 19 of the spiders 18.

The can body will then be carried forward beneath the can cap feeding mechanism 29. This feed mechanism has been previously described in my co-pending application entitled "Can cap feeding mechanism" and generally considered, comprises a pair of parting knives 30 connected by a cross-head 31. The cross-head also carries a pusher bar 32. The feed rails, as shown in Fig. 2, are formed with a ledge 33 which is interrupted by an inclined groove 34. The ledge normally holds the stack of cans 20 and as alternate reciprocation of the members 30 takes place the lower-most can cap will be cut out and passed down the throat of the groove 34 and allowed to then travel along the trackways 20 and 22.

In order to insure a positive feed for the can caps independent of the movement of spider 18 and the can body, a plurality of radial swinging cap feed arms 35 are provided. These arms are pivoted for vertical movement and are carried by the can feed spider 18. As more clearly shown in Fig. 3 of the drawing the arms comprise a sleeve swinging finger 36 having an upwardly extending end which engages the lower-most can cap fed from the stack 37. The opposite ends of the feed members 35 are turned upwardly, as indicated at 38. These members are fitted with rollers 39 which continuously pass along an eccentric groove 40 in a fixed face cam 41. This groove is so designed as to cause the bell cranks 35 to oscillate from the extreme upper-most position as indicated at the right hand of Fig. 3 to the extreme lower-most position as indicated at the left hand of Fig. 3. This mechanism will reach the lower-most can cap and gradually feed it down onto the can body without danger of tipping or binding due to the fact that the lever agrees in its movement with the downward travel of the can cap. It will, of course, be understood that these bell crank members travel with the spider 18 and by reference to Fig. 1 of the drawing it will be noted that the arm portions 36 extend directly in the rear of the various recesses 19 of the spider, thus insuring that the cap will be carried down with a complementary can body.

The driving mechanism of the present invention comprises a plurality of gears form-

ing trains driven from a suitable source of supply. The gear 42 is secured to the lower end of shaft 43. This shaft is pinned to the spider 18 and affords a driving movement therefor. The gear 42 is in mesh with a gear 44 carried by a shaft 45. The shaft 45 supports the sprocket 26 and drives same while an idler shaft 46 supports the sprocket 25. Shaft 47 is driven by a suitable train of gears and this shaft in turn operates a driving cup 48 carrying a pawl member 49. The pawl is normally held out of engagement with a recess 50 in a pin 51 by means of a trip lever 52. This lever, as more clearly shown in Fig. 1, is a part of a bell crank 54, the opposite end of said crank extending into the normal path of travel of the cans and being swung by the presence of a can thereagainst. The mechanism involved with this structure is more clearly shown in my co-pending application concerned with can cap feed mechanism.

In operation of the present invention, the various shafts are driven by the suitable gear train and the feed disc 13 is caused to rotate in the direction of the arrow —a—. As the cans are fed to this disc they will be successively engaged by the fingers 15. If it should so happen that the cans have not been fed to occur between the fingers 15, these fingers will be depressed and will thus prevent mutilation of the can, allowing the next finger to engage the can and to feed it forwardly. Here it will be delivered between the guide rails 16 and 17 and will then be engaged by the fingers 28 of the variable sprocket chain 24. The speed of the cans will be gradually accelerated until they reach a point where they come into register with the recesses 19 of the feed spider 18. Here they will assume a greater speed and will be delivered forwardly to pass along the guide rail 20. Simultaneous with this movement the can will swing the bell crank 54 and operate the shaft 51 thus causing reciprocation of the can cap feed bars through rotation of crank 60 and pitman rod 62. A can cap will thus be cut from the bottom of the stack and fed through the throat 34 of the bars 33; and member 32 brings the cap forwardly to be engaged by fingers 35 and 36. At this time the upwardly extending arm 36 occurring behind the recess carrying the can will engage the cap and carry it forwardly and downwardly along the trackways 20 and 22 to a point substantially opposite the point at which the spider receives the can. Here it will be received by the first turret of the double seaming machine and the can and cap will thus be carried forward to complete the first movement of the seaming operation.

While I have shown the preferred form of my invention as now known to me, it will

be understood that various changes in the construction, combination and arrangement of parts may be made by those skilled in the art without departing from the spirit of the 5 invention as claimed.

Having thus described my invention what I claim and desire to secure by Letters Patent is:

1. In a can capping machine, a can feed device comprising a slowly traveling initial feed member, a rapid traveling final feed member and means interposed between said devices and having a member to transfer cans from one to the other of said devices and means 10 for causing the rate of travel of the can engaging portion of the said member to gradually accelerate during a portion of its travel.
2. In a can capping machine, a constantly 20 rotating device for feeding cans, said device operating at a uniform speed of travel, a slow feed initial feeding device for receiving a flow of cans, traveling members for positively and consecutively engaging the cans 25 fed by said initial device and delivering them to the first named feed device and means for causing the rate of travel of the can engaging portions of the said members to gradually accelerate during a portion of 30 their travel.
3. In a can capping machine, means for feeding cans comprising a horizontally disposed rotary disk onto which a flow of cans is fed, a plurality of positive feed members 35 for continuously carrying the cans from said disk, a second continuously rotating feed device operating at a higher speed than that of the disk and to which the cans are carried by said positive feed members and 40 means for causing the rate of travel of the can engaging portions of the positive feed members to gradually accelerate during a portion of 45 their travel.

4. In a can capping machine, means for feeding cans comprising a horizontally disposed rotary disk onto which a flow of cans is fed, a plurality of positive feed members for continuously carrying the cans from said disk, a second continuously rotating feed device operating at a higher speed than that of the disk to which the cans are carried by the said positive feed members and means for causing the rate of travel of the can engaging portions of the said members to accelerate during a portion of the travel of the same, said rate of travel increasing from that of the rate of travel of a can while carried by the disk to the rate of travel of the can while carried by the second feed means. 50 55

5. An accelerating can feed device comprising a pair of sprockets, a chain traveling therearound, a plurality of feed members carried by the chain, means for driving the sprockets at a constant rate of travel, and means for causing the rate of travel of the outer engaging portions of the feed members to gradually accelerate during a portion of 60 their travel. 65

6. A can cap feed device comprising an initial feed means operating at a slow constant rate of speed, a final feed means operating at a relatively high constant rate of speed, a cam trackway for conducting cans from the first to the second feed means, a positively operating drive means for accelerating the rate of travel of the cans along the trackway including spaced sprockets, a chain traveling therearound, a plurality of feed fingers carried by the chain and projecting therefrom, means for driving the sprockets at a constant rate of travel, and means for causing the rate of travel of the outer engaging portions of the feed fingers to gradually accelerate during a portion of 70 75 80 their travel.

HENRY L. GUENTHER.
